DESIGN FOR A FIGURE TOY

Lawrence R. Adrian, Iowa City, Iowa

Application April 15, 1936, Serial No. 62,139

Term of patent 3½ years

To all whom it may concern:

Be it known that I, Lawrence R. Adrian, a citizen of the United States, residing at Iowa City, in the county of Johnson and State of Iowa, have invented a new, original, and ornamental Design for a Figure Toy, of which the following is a specification, reference being had to the accompanying drawing, forming part thereof.

I claim:—

The ornamental design for a figure toy as shown.

LAWRENCE R. ADRIAN.
